UNITED STATES PATENT OFFICE.

HERMANN O. MÜLLER, OF NEW YORK, N. Y.

DESIGN FOR A LAMP-HOLDER.

SPECIFICATION forming part of Design No. 28,734, dated May 31, 1898.

Application filed October 30, 1897. Serial No. 656,970. Term of patent 14 years.

To all whom it may concern:

Be it known that I, HERMANN O. MÜLLER, a subject of the Emperor of Germany, and a resident of New York, in the county and State 5 of New York, have invented and produced a new and original Design for Lamp-Holders, of which the following is a specification, reference being had to the accompanying drawing, forming a part thereof.

The accompanying drawing represents a design which embodies my invention.

The leading feature of my design consists in a lamp-holder which comprises the representation of a flower-like figure mounted upon 5 a stem which rises from a circular base.

The drawing represents a flower, in which 1 represents the outside shell formed of three

petals. Inside of this outside shell is placed the inside shell 2, which is also formed of three petals, the petals of one shell being made to alternate with the other. This flower-like figure is mounted upon the stem 3, which rises from the base 4.

Having thus described my invention, I claim—

The design for an ornamental lamp-holder, substantially as shown and described.

In testimony whereof I affix my signature in presence of two witnesses.

HERMANN O. MÜLLER.
